CLAIM

The ornamental design for a medical device applicator and sleeve assembly, as shown and described.

DESCRIPTION

FIG. 1 is a top, front, and right side perspective view of a first embodiment of a medical device applicator and sleeve assembly of our design;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof; and

FIG. 8 is a reference exploded view thereof.

FIG. 9 is a top, front, and right side perspective view of a second embodiment of a medical device applicator and sleeve assembly of our design;

FIG. 10 is a top view thereof;

FIG. 11 is a bottom view thereof;

FIG. 12 is a right side view thereof;

FIG. 13 is a left side view thereof;

FIG. 14 is a front view thereof;

FIG. 15 is a rear view thereof; and

FIG. 16 is a reference exploded view thereof.

FIG. 17 is a top, front, and right side perspective view of a third embodiment of a medical device applicator and sleeve assembly of our design;

FIG. 18 is a top view thereof;

FIG. 19 is a bottom view thereof;

FIG. 20 is a right side view thereof;

FIG. 21 is a left side view thereof;

FIG. 22 is a front view thereof;

(Continued)

FIG. 23 is a rear view thereof; and
 FIG. 24 is a reference exploded view thereof.
 FIG. 25 is a top, front, and right side perspective view of a fourth embodiment of a medical device applicator and sleeve assembly of our design;
 FIG. 26 is a top view thereof;
 FIG. 27 is a bottom view thereof;
 FIG. 28 is a right side view thereof;
 FIG. 29 is a left side view thereof;
 FIG. 30 is a front view thereof;
 FIG. 31 is a rear view thereof; and,
 FIG. 32 is a reference exploded view thereof.
 The dash-dash broken lines form portions of the medical device applicator and sleeve assembly and components of the medical device applicator and sleeve assembly that form no part of the claimed design.
